UNITED STATES PATENT OFFICE

2,489,650

ADJUSTABLE LAMP SUPPORT

Wiley Allen Landrum, Hattiesburg, Miss.

Application November 21, 1946; Serial No. 711,277

2 Claims. (Cl. 248—124)

1

This invention relates to new and useful improvements and structural refinements in adjustable lamps, more specifically, adjustable desk lamps, floor lamps, or the like, and the principal object of the invention is to provide a device of the character herein described, in which the source of light and the shade associated therewith may be easily and conveniently adjusted with respect to the lamp base.

A further object of the invention is to provide an adjustable lamp which is simple in construction, pleasing in appearance, and which may be readily disassembled for purposes of inspection or repair.

Another object of the invention is to provide an adjustable lamp which will not easily become damaged and which will readily lend itself to economical manufacture.

An additional object of the invention is to provide an adjustable lamp which is otherwise well adapted for the purpose for which it is intended.

With the above more important objects in view and such other objects as may become apparent as this specification proceeds, the invention consists essentially of the construction and arrangement of parts as shown in the accompanying drawings in which:

Figure 1 is a perspective view of the invention.

Figure 2 is a cross-sectional view, taken substantially in the plane of the line 2—2 of Figure 1.

Figure 3 is a cross-sectional view, taken substantially in the plane of the line 3—3 in Figure 1.

Figure 4 is an exploded perspective view showing a cradle and a knuckle used in the invention.

Figure 5 is an underside perspective view of a shade used therein, and

Figure 6 is a side elevation of a modified embodiment of the invention.

Like characters of reference are used to designate like parts in the specification and throughout the several views.

Referring now to the accompanying drawings in detail, the invention consists of an adjustable lamp designated generally by the reference character 10, the same embodying in its construction a substantially circular base 11 consisting of an inner member 12 positioned under an inverted dish-like cover 13.

The latter is secured to the member 12 in any suitable manner and it will be noted that the member is formed in the underside thereof with an elongated recess or chamber 14, the purpose of which will be hereinafter more fully explained.

2

The base member 12 may also be provided on the underside thereof with a plurality of rubber pads 15 for obvious reasons.

The cover 11 is provided with an opening 16 communicating with the chamber 14 of the base member 12 and the opening 16 is surrounded by an upwardly extending cradle 17. This cradle is best shown in the accompanying Figure 4, wherein it will be noted that it consists of a pair of spaced parallel ears 18 connected together by the side members 19. Each of the ears 18 is formed with a central aperture 20 and with a pair of diametrically opposed recesses 21, one of these recesses simply assuming the form of a notch provided in the marginal edge of the ear.

The recesses 21 are arcuate and concentric with respect to the apertures 20.

A knuckle, assuming the form of a tubular member 22 is rotatably positioned in the cradle 17 between the ears 18, the bore of the member 22 being provided at the ends thereof with chamfered portions 23.

The knuckle 22 is also provided with a laterally projecting extension 24 which is hollow and communicates with the bore of the knuckle. It will be noted that the extension 24 projects through the opening 16 into the chamber 14 of the base.

A pair of bearing blocks 25 are associated with the knuckle 22, each consisting of a tubular shank 26 provided at one end thereof with a flange 27. This flange is, in turn, equipped with a pair of diametrically opposed, beveled lugs 28, these being of an arcuate configuration and being concentric with respect to the shank 26.

The shanks 26 are receivable in the apertures 20 of the cradle 17 and the lugs 28 extend through the recesses 21 so that the beveled edges thereof rotatably engage the chamfered portions 23 of the knuckle 22.

An assembly screw 29, provided with a nut 30, extends through the blocks 25, through the ears 18 and through the bore of the knuckle 22, whereby the various components are secured together. It will be noted that the blocks 25 are equipped with suitable counter-bores to receive the head of the bolt 29 and the nut 30.

The knuckle 22 carries an upright, tubular standard 31, the upper end of the latter forming a fork 32 which straddles a suitable extremity 33 of a carrier 34. A pin 35 is employed for pivotally connecting the fork 32 to the extremity 33 of the carrier.

The carrier 34 is configurated substantially as

shown and is provided with a conventional socket 36 to receive an incandescent lamp 37.

The carrier 34 is also provided with a pair of supporting pads 38 and 39, the former being slidably receivable in an offset strap 40 secured to a reinforcing plate 41 which, in turn, is provided on the inner surface of a suitable lamp shade 42.

The supporting pad 39 is equipped with a bolt 43 which extends through a suitable aperture 44 provided in the shade structure and carries a knurled nut 45. It will be apparent that in this manner, the shade 42 is removably attached to the carrier 34.

The base 11 is provided with a clevis pin 46, to which is pivotally connected as at 47 one end of a control bar 48. The remaining end of this bar is pivoted as at 49 to an adjusting screw 50, the shank of the latter operatively engaging a screw-threaded bore provided in an adjusting nut 51. This nut is freely rotatable in a suitable aperture provided in the carrier 34.

It should be added that if desired, the aforementioned standard 31 may be equipped with a hand grip 52 which extends partially along the length of the standard and is secured thereto by a set screw 53.

The current conductors 54 are taken from the lamp socket 36 through the extension 33 of the carrier 34 and thence downwardly through the standard 31. Thereupon, the conductors 54 pass through the knuckle 22 and through the extension 24 associated therewith into the chamber 14 in the base 11 and are connected to an extension cord 55 terminating in a conventional attachment plug 56. The cord 55 passes outwardly from the chamber 14 through a grommet 57 provided in the marginal flange of the cover 13 and it will be also noted that the cover carries a push button switch 58 which is wired in series with the lamp 37.

The underside of the chamber 14 is closed by a removable cover plate 59 which is secured to the base member 12 by means of a plurality of screws 60.

When the invention is placed in use, it will be found that the position of the lamp 37 and the associated shade 42 may be readily adjusted with respect to the base 11 by virtue of the pivoted standard 31 and the pivoted control bar 48. The control bar extends in a spaced parallel relation to the standard and, accordingly, the shade 42 will remain at all times substantially parallel to the base 11, regardless of the positional adjustment of the lamp. This is exemplified by the phantom lines 61 in the accompanying Figure 1.

In addition, the carrier 34 and the shade 42 may be adjusted with respect to the standard 31, this being accomplished by simply rotating the nut 51 and thereby "tilting" the carrier 34 about the pin 35.

Referring now to the modified embodiment of the invention illustrated in the accompanying Figure 6, the adjustable lamp designated generally by the reference character 70 is similar to the aforementioned lamp 10, but is primarily intended for use as a floor lamp rather than as a desk lamp, as in the embodiment already described.

The lamp 70 includes the standard 71 provided with a hand grip 72 and a control bar 73, the same supporting a carrier (not shown) for the lamp and shade 74.

The lower end portion of the standard 71 is pivoted to a cradle assuming the form of a sleeve 75, the latter also being provided with a clevis 76 to which the lower end of the bar 73 is pivotally attached.

The sleeve 75 is mounted at the upper end of an upright shaft 77, the lower end of which is, in turn, secured to a suitable base 78.

When this embodiment of the invention is placed in use, the lamp may be conveniently adjusted as exemplified by the phantom lines 79, in the manner already described in connection with the lamp 10. If desired, the provision of a switch in the base 78 may be dispensed with and a suitable switch may be associated directly with the lamp socket.

It is believed that the advantages and use of the invention will be clearly understood from the foregoing disclosure and, accordingly, further description thereof at this point is considered unnecessary.

While in the foregoing there has been shown and described the preferred embodiment of this invention it is to be understood that minor changes in the details of construction, combination and arrangement of parts may be resorted to without departing from the spirit and scope of the invention as claimed.

What I claim as my invention is:

1. In an adjustable lamp, a base, a standard pivoted at one end thereof to said base, a lamp carrier pivoted to the remaining end of said standard, said carrier being formed with an aperture, an internally screw-threaded nut freely rotatable in said aperture, a screw adjustable in said nut, and a control bar pivoted at one end thereof to said base, the remaining end of said bar being pivoted to said screw.

2. In an adjustable lamp, a base formed with an opening, a cradle provided on said base at the edges of said opening, said cradle including a pair of spaced ears each formed with a central aperture and with diametrically opposed recesses, a substantially tubular knuckle member rotatably positioned between said ears and formed at its ends with chamfered bore portions, a pair of bearing blocks each including a tubular shank, a flange at one end of said shank and a pair of diametrically opposed and bevelled lugs on said flange, said shanks being receivable in said apertures, said lugs extending through said recesses and frictionally engaging the chamfered bore portions of said knuckle member, an assembly bolt extending through said member and bearing blocks, a standard connected to said knuckle member, and a lamp carrier on said standard.

WILEY ALLEN LANDRUM.
